UNITED STATES PATENT OFFICE.

HARRY LUTE GROW, OF FAIRBANKS, TERRITORY OF ALASKA.

MINING MACHINE.

Application filed December 16, 1924. Serial No. 756,300.

To all whom it may concern:

Be it known that I, HARRY LUTE GROW, a citizen of the United States, and resident of Fairbanks, Territory of Alaska, have invented certain new and useful Improvements in Mining Machines, of which the following is a specification.

My invention relates to improvements in mining machines and it consists of the constructions, combinations and arrangements herein described and claimed.

An object of the invention is to provide a small but sturdy machine for facilitating various mining and cutting operations, for example, drift mining, tunneling, open cut excavating, loading, road building, etc.

A further object of the invention is to provide a machine for the purpose described having a discharge conveyor which may be turned laterally independently of the rest of the machine.

Another object of the invention is to provide a mining machine in which all of the important parts are mounted upon a main base or frame which in turn can be revolved upon a turn table carried by a truck, thereby permitting the adjustment of the elevator and conveyor at various angles in respect to the truck.

Another object of the invention is to provide in combination with the elevator such means as can be forced into the surface in back, to act as a chock to brace the machine when the elevator enters the material to be loaded.

Other objects and advantages will appear in the following specification reference being had to the accompanying drawings, in which—

Figure 1 is a side elevation of the improved mining machine.

Figure 2 is a detail vertical section taken substantially on the line 2—2 of Figure 1, and illustrating the turn table structure.

Figure 3 is a detail plan view of the movable turn table plate.

Figure 4 is a side elevation of the improved machine taken from the side opposite that in Figure 1.

Figure 5 is a detail front elevation of the excavating elevator.

Figure 6 is a detail section on the line 6—6 of Figure 5.

Figure 7 is a longitudinal section of one of the elevator chocks.

Figure 8 is a detail cross section on the line 8—8 of Figure 7.

Figure 9 is a plan view of the mining machine.

Figure 10 is a detail side elevation illustrating a rail clamp.

Figure 11 is a cross section on the line 11—11 of Figure 10.

In carrying out the invention provision is made of a truck, composed generally of longitudinal channels 1, axles 2, wheels 3 and any appropriate arrangement of braces to complete the truck. The wheels of the truck run upon rails 4, and these are laid as may be needed so that the mining machine may be advanced as the cut increases.

A turn table plate 5 (Fig. 2) has depending flanges 6 through which bolts 7 pass to secure the plate to the channels 1. This plate assists in the bracing of the truck. It includes a race or bearing surface 8 upon which the roller bearings 9 run. These bearings are carried by rings 10.

Formed on the plate 5 is a boss 11 which carries a kingbolt 12 by which the main frame or base is held in place upon the truck. The main frame, like the truck 1, has longitudinal channels 13. These are bolted or otherwise secured at 14 to upstanding flanges 15 (Figs. 2 and 3) of the movable turn table plate 16. This plate revolves upon the rollers 9, there being a suitable race 17 to provide a proper bearing surface.

A bearing plate 18, secured upon the main frame, both conceals the turn table plate 16 and provides a bearing for a large double drive gear comprising spur and beveled teeth 19 and 20 respectively.

The main frame is capable of turning in its entirety upon the truck 1, this together with all of its carried parts. This provides the advantage of directing the cutting and elevating operations from practically all radial positions while the truck 1 remains in place on the track. A boss 21 on the movable plate 16 receives the bolt 12 and thus assists in keeping the main frame centered on the roller bearings 9.

A yoke 22 supports the lower shaft 23 of a conveyor. The yoke is held in place upon the double gear by the head of the king bolt but is capable of turning independently of the double gear so that the conveyor may be adjusted at various angles without disturb-

ing other parts. The conveyor consists of a slatted belt 24 which runs over rollers 25 at the extremities, one being carried by the shaft 23, the other by a shaft 26 at the free 5 end of the conveyor. The upper strand of the belt traverses a trough 27.

A cable yoke 28 supports the conveyor. The bight of this yoke passes over a sheave 29. This sheave is stationarily mounted on 10 top of the machine. No adjustment of the discharge trough or stacker 27 is intended.

Mounted on top of the machine is a fixed cross piece 61 in which the unthreaded end of a screw shaft 62 has swivel mounting. 15 The cross piece 61 has apertures for a pair of guide rods 63 which extend forward and have permanent fastening in the head piece 64.

The fastening of the guide rods 63 includes a collar 65 which in each case abuts one 20 side of the head piece and washer and pin connections 66 and 67 securing the guide rods on the opposite side of the head piece. The adjacent ends of the guide rods terminate 25 in eyes 68 to which the cables 50 are attached. The screw shaft 62 has threaded engagement with the head piece 64 and it carries a head 69 on the free end. This head has a plurality of openings 70 to receive a 30 wrench bar for the purpose of turning the screw shaft and moving the head piece back and forth.

Situated on one end of the conveyor drive shaft 23 is a large beveled gear 30 which 35 meshes with the beveled gear 20 of the double gear. This double gear receives its driving power from an electric motor 31 whence it is transmitted by the following gear train.

A pinion 32 on the motor shaft drives a 40 pinion 33 on a counter-shaft 34. This shaft carries a worm pinion 35 which meshes with a worm gear 36. The shaft 37 of this gear carries a spur pinion 38 which meshes with a spur gear 39 on the elevator drive shaft 40.

45 The opposite end of this shaft carries a pinion 41 (Fig. 4) which drives a pinion 42 on the upright shaft 43. This shaft carries a spur pinion 44 which meshes with the spur gear 19 and thus drives the double gear.

50 Mounted upon the main frame 13 is a steel plate supporting frame 45. This frame appears like and functions much on the order of a clutch. It provides a support for the shafts 37 and 40 of the aforesaid gear train (Fig. 1) as well as for the sheave 29 and its 55 associated parts. Moreover, it protects the members mentioned of the gear train from being fouled with dirt from the elevator at the front of the machine. This elevator 60 consists of buckets 47 so linked together as to form a chain, a chain as such not being necessary.

These buckets are specially made for digging purposes and to this end they are made 65 quite sharp, like claws, so that even quite

hard material can be loosened and carried away. The elevator buckets run over properly shaped wheels upon the upper and lower shafts 40 and 48 such as shown at 49 upon the lower shaft 48 in Figure 6.

70 The cables 50 supports the elevator by being attached to the side plate 51. The shafts 40 and 48 are journaled on these side plates. The elevator extends up into the hood 45, and it is by virtue of being so disposed in respect to the hood that the gears of the aforesaid train are protected to a large extent. The cables 50 run over pulleys 52 which are suitably mounted on the hood.

75 It has been explained that these cables are attached to the eyes 68 of the guide rods 63. It is by this means that the cables and consequently the elevator 51, are supported. Adjustments of the elevator are made by 80 turning the screw shaft 62 and thereby moving the head piece 64 back and forth.

85 Means is provided for bracing the mining machine when the excavator buckets 47 of the elevator impact the material to be loaded. These means comprise tubular bars 53 which are preferably non-circular in cross section. Split clamps 54 receive the bars. One of the clamps is shown in detail in Figures 7 and 8.

90 The clamp 54 is secured to the elevator side 51 by means of a shouldered and headed bolt 55. The opposite side of the clamp carries a threaded nipple 56 upon which, when the clamp wheel 57 is screwed, a clamping action 95 on the rod 53 takes place securing the latter in any particular adjustment. The clamping action is also exerted against the head of the bolt 55 and inasmuch as the head of the bolt presses against the rod 53 (Figure 100 105 8) the rod is at once held in a particular angular position. The bolt itself is fixed so that it cannot turn.

105 On the lower extremity of the rod 53 is a shoe 58 which has heavy spikes 59 for the 110 purpose of entering and gripping the ground. It is readily seen that when the bars 53 and shoes 58 are fixed in position, provision is made of an effective chock which prevents any back motion of either 115 the elevator 51 or the mining machine. The chocks operate most effectively in respect to the elevator 51, and although it will have a bracing action on the mining machine itself yet too much is not to be expected. Suitable 120 blocks may therefore be fitted behind the wheels 3 in actual practice to supplement the chocks. The shoes 58 are pivoted to the respective bars at 60.

The operation.

125 The electric motor 31 furnishes driving power for both the conveyor 27 and the elevator 51. This power is transmitted by a gear train partly illustrated in Figure 1 130

and completed in Fig. 4. The elevator 51 is driven from the shaft 40 which carries gears 39 and 41 forming part of the train. This train terminates at the spur pinion 44 which meshes with and drives the spur gear 19 of the large double gear.

Bearing for the double gear is furnished by the plate 18 (Fig. 2) on the main frame 13. Turning of this gear causes the operation of the conveyor by engagement of the beveled gear 30 with the gear 20 of the double gear. The main frame 13 and all of its carried parts may be bodily turned upon the rollers 9 of the turn table 16 (Fig. 2). This permits of adjusting the conveyor and elevator at various radial positions in respect to the trucks 1 which for this purpose may be regarded as fixed.

Independent adjustment of the conveyor 27 may be made by merely turning the yoke 22 upon the king bolt 12. Upon turning the conveyor the gear 30 will simply move back and forth in reference to the gear 20 without interfering with the revolution of the last gear.

The mining machine is advanced into the material by pushing the truck 1, and as the mining machine advances the excavator buckets 27 of the elevator will dig in and elevate the material to the point of discharge above the conveyor 27. The cutting edges of the buckets 27 are purposely made sharp so that hard or frozen material may be removed quite easily. As already stated in the description above the mining machine is adaptable to a variety of purposes, for example, ditch digging, road building, excavating and loading, tunneling, etc.

Another feature in favor of the machine is its comparative small size. In practice the machine will be less than five feet in height and approximately seven feet long. The truck 1 and frame 13 will be as short as possible, and altogether the machine will be quite compact, thereby readily adapting it to the particular uses specified.

It should be mentioned in conclusion that provision is also made for holding the trucks 1 from moving backward on the rails. This provision is a rail clamp 71 (Figs. 10 and 11) consisting of a pair of plates secured by a bolt 72 and fitted with a nut 73 having a wrench handle 74. The ends 75 and 76 of the plates are formed to properly engage the head of the rail, whereupon the nut 73 is tightened by means of the wrench handle to secure the rail clamp in place.

While the construction and arrangement of the improved mining machine as herein described and claimed is that of a generally preferred form, obviously modifications and changes may be made without departing from the spirit of the invention or the scope of the claims.

I claim:—

1. A mining machine having an elevator including excavator buckets, a frame including side plates by which the elevator is supported, a split clamp on each side plate including a split and threaded nipple, a bar carried by each clamp, a spiked shoe carried by each bar to engage the ground and brace the elevator against the impact of the buckets when excavating, a bolt fixedly carried by each side plate upon which each clamp is mounted, the head of each bolt bearing against the respective bar, and means on the nipples including hand wheels for tightening the clamps both upon the bolt and against the bars to hold them in adjusted positions.

2. A mining machine having a main frame, a supporting frame mounted on top thereof having a shape to define a hood, an elevator having the discharge end extending into the hood, and driving means for the elevator including a train of gearing situated outside of the hood thereby being protected from material escaping from the elevator.

3. A mining machine having a main frame, a supporting frame carried thereby defining a hood, a train of gears situated outside of the hood including gear shafts, one of said shafts extending through the hood from side to side, an elevator having the discharge end extended into the hood and mounted upon the last shaft, and means mounted on top of the hood supporting the free end of the elevator.

4. A mining machine having a main frame, a supporting frame carried thereby defining a hood, a train of gears situated outside of the hood including gear shafts, one of said shafts extending through the hood from side to side, an elevator having the discharge end extended into the hood and mounted upon the last shaft, means mounted on top of the hood supporting the free end of the elevator, and means carried by the elevator adjacent to the free end for gripping the ground, bracing the elevator and augmenting said supporting means.

5. A mining machine having a main frame, supporting means mounted thereon including a hood, a conveyor drive shaft extending across the hood from side to side and projecting at both ends, an elevator having one end extended into the hood and mounted upon said shaft for driving, a train of driving gears including a gear on one end of the shaft and a pinion at the other, a conveyor having a shaft situated immediately in front of the hood, and gearing driven from said pinion for operating the conveyor as the elevator is driven.

6. A mining machine having a main frame, supporting means mounted thereon constituting a hood, a combined spur and beveled gear journaled upon the main

frame, a conveyor having a drive shaft, a bevel gear carried by said shaft meshing with the aforesaid beveled gear, a yoke by which the conveyor is supported at one end upon said combined gear, an elevator drive shaft journalled upon the hood and having each end extending therebeyond, an elevator having the discharge end extending into the hood and mounted upon said drive shaft to discharge into the conveyor, and common driving means including a gear on one end of the elevator shaft and a pinion on the other, and drive means for transmitting motion from said pinion to the spur teeth of said combined gear.

7. A mining machine having a main frame, supporting means mounted thereon constituting a hood, a combined spur and beveled gear journalled upon the main frame, a conveyor having a drive shaft, a beveled gear carried by said shaft meshing with the aforesaid beveled gear, a yoke by which the conveyor is supported at one end upon said combined gear, an elevator drive shaft journalled upon the hood and having each end extending therebeyond, an elevator having the discharge end extending into the hood and mounted upon said drive shaft to discharge into the conveyor, and common driving means including a gear on one end of the elevator shaft and a pinion on the other, and drive means for transmitting motion from said pinion to the spur teeth of said combined gear, and means by which said yoke is swivelly mounted upon the combined gear so that the conveyor may be radially turned independently of other mechanism.

8. A mining machine having a main frame, supporting means mounted thereon comprising a hood, an elevator having the discharge end extending beneath the hood, a drive shaft upon which said end of the elevator is mounted, a conveyor into which the elevator discharges, a drive shaft upon which the conveyor is mounted, a yoke by which said shaft is carried, a combined spur and beveled gear revolvably mounted upon the main frame, a gear on the conveyor drive shaft meshing with the bevel gear of said double gear, common drive means for both the elevator and conveyor having a shaft having a spur pinion meshing with the spur gear of said double gear, and means by which the double gear is held in place upon the main frame and upon which said yoke has swivel mounting permitting turning of the conveyor while in operation independently of other mechanism.

9. A mining machine having a main frame including a plate constituting a bearing, a combined spur and bevel gear resting upon said plate, a conveyor having a drive shaft at one end, a gear carried by said shaft meshing with the bevel gear of said combined gear, means by which the free end of the conveyor is supported, a yoke in which the drive shaft is journaled and upon which the conveyor is vertically movable by adjusting said supporting means, and means including a king bolt by which both the yoke and combined gears are held in place upon said bearing plate, said yoke being horizontally turnable in respect to the combined gear while the latter revolves upon said plate.

10. A mining machine having a main frame composed of longitudinal channels, a turn table plate affixed to the channels, a bearing plate affixed to the channels concealing the turn table plate, a conveyor having a drive shaft, a yoke in which the shaft is journaled, a gear on said shaft, a large gear having bearing on said bearing plate and providing a support for the yoke, a truck having a complementary turn table plate, roller bearings situated between the turn table plates, and means including a king bolt securing various of the foregoing parts together, providing a swivel mounting for the yoke, holding the large gear in place on the bearing plate and keeping the turn table plates together.

11. A mining machine having an elevator, means including cables for raising and lowering the elevator, means including a head piece to which the cables have common connection, means including a screw for moving the head piece and thereby either pull or relax on the cables, and means for guiding the movement of the head piece.

12. A mining machine having a hood, an elevator pivotally mounted on the hood, and means on top of the hood for raising and lowering the elevator, said means comprising a head piece, a screw shaft having threaded engagement with the head piece and having means for turning the screw shaft to move the head piece, a cross piece upon which the screw has swivel mounting, guide rods carried by the movable head piece and extending through apertures in the cross piece, said guide rods having eyes, cables attached to the eyes and to the elevator, and pulleys mounted upon the hood over which the cables pass.

HARRY LUTE GROW.
